UNITED STATES PATENT OFFICE.

BYRON D. JACKSON, OF ERIE, PENNSYLVANIA, ASSIGNOR TO MODERN TOOL COMPANY,
OF ERIE, PENNSYLVANIA, A CORPORATION OF PENNSYLVANIA.

TAIL-FOOT FOR LATHES.

1,078,857.

Specification of Letters Patent. Patented Nov. 18, 1913.

Application filed November 7, 1912. Serial No. 730,098.

To all whom it may concern:

Be it known that I, BYRON D. JACKSON, a citizen of the United States, residing at Erie, in the county of Erie and State of Pennsylvania, have invented new and useful Improvements in Tail-Feet for Lathes, of which the following is a specification.

This invention relates to a tail-foot for lathes and consists in certain improvements 10 in the construction thereof as will be hereinafter fully described and pointed out in the claims.

In forming a tail-foot for grinding machines and similar articles it is necessary to 15 hold the spindle carrying the center with great rigidity so that great accuracy may be had in the performance of the machine.

The object of the present invention is to improve a tail-foot in this particular.

20 The invention is illustrated in the accompanying drawings as follows:

Figure 1 shows a plan view of a tail-foot. Fig. 2 is an end view partly in section on the line 2—2 in Fig. 1.

25 1 marks the lathe center, 2 the work carried by the center, and 3 the spindle carrying the center. The spindle is carried in a bearing 4 arranged in the tail-foot block 4^a. The bearing 4 is split longitudinally for a 30 distance back from the end of the bearing spindle, this separation being indicated at 6. In order to give the part of the bearing thus separated a uniform gripping surface throughout a sufficient length to assure the 35 alinement of the spindle, the bearing is cut transversely at 7 so that the forward part of the bearing will be free to spring the clamp and spindle. Lugs 8 extend upwardly from the bearing 4 along the lines of separation 6. These lugs form a dove-tail and have the wedge surfaces 9, the wedge extending in a longitudinal direction. A 40 clamping plate 10 extends over the lugs 8 and has the downwardly extending lips 10^a, the inner surfaces of which correspond to the surfaces 9 of the lug 8. A lever 11 is 45 pivotally mounted on the bearing 4 by a pin 12 and is connected with the plate 10 by means of the pin 13.

50 The spindle is moved by any desired mechanism, the hand wheel 5 being arranged for this purpose, and when the center is properly adjusted in the work the

lever 11 is operated forcing the plate 10 forward. The wedge surfaces on the inner 55 edge of the lips 10^a engaging the wedge surfaces 9 force the free side of the bearing 4 into engagement with the spindle, thus securely clamping the spindle in accurate alinement with the surface of the bearing. 60 The frictional engagement with the wedge surfaces is sufficient to hold the clamping plate in position during the operation on the work. At the completion of the operation the lever 11 is swung to free the plate and 65 the center can then be withdrawn by the operation of the hand wheel on the spindle in the usual manner.

What I claim as new is:—

1. In a tail-foot for lathes, the combination of a spindle; a spindle carrying bearing split longitudinally and having lugs along the line of separation, said lugs forming a longitudinally extending wedge; a clamp plate arranged over the lugs having 75 wedge surfaces engaging the wedge surfaces on the lugs; means for forcing the clamp plate longitudinally; and means for moving the spindle longitudinally. 80

2. In a tail-foot for lathes, the combination of a spindle; a spindle carrying bearing split longitudinally and having dove-tail lugs along the line of separation, said dove-tail lugs forming a longitudinally extending wedge; a clamp plate arranged over the lugs having wedge surfaces engaging the wedge surfaces on the lugs; means for forcing the clamp plate longitudinally; and means for moving the spindle longitudinally. 85

3. In a tail-foot for lathes, the combination of a spindle; a spindle carrying bearing split longitudinally and having lugs along the line of separation; said lugs forming a longitudinally extending wedge; a clamp plate arranged over the lugs having 95 wedge surfaces engaging the wedge surfaces on the lugs; and a lever pivotally mounted on the spindle carrying bearing for operating the clamp plate. 90

4. In a tail-foot for lathes, the combination of a spindle; a spindle carrying bearing split longitudinally through a part of its surface and having a transverse slot extending from the longitudinal separation, said bearing being provided with lugs extending along the line of separation, said 105

lugs forming a longitudinally extending wedge; a clamp plate arranged over the lugs having wedge surfaces engaging the wedge surfaces on the lugs; means for forcing the 5 clamp plate longitudinally; and means for moving the spindle longitudinally.

In testimony whereof I have hereunto set

my hand in the presence of two subscribing witnesses.

BYRON D. JACKSON.
